F. ZACCARD AND T. P. McDONOUGH.
LIFE SAVING APPAREL.
APPLICATION FILED JUNE 17, 1918.

1,314,299.

Patented Aug. 26, 1919.

UNITED STATES PATENT OFFICE.

FELIX ZACCARD AND THOMAS P. McDONOUGH, OF CHICAGO, ILLINOIS.

LIFE-SAVING APPAREL.

1,314,299.

Specification of Letters Patent. Patented Aug. 26, 1919.

Application filed June 17, 1918. Serial No. 240,413.

To all whom it may concern:

Be it known that we, FELIX ZACCARD and THOMAS P. McDONOUGH, citizens of the United States, residing at Chicago, in the 5 county of Cook and State of Illinois, have invented certain new and useful Improvements in Life-Saving Apparel, of which the following is a specification.

Our invention relates to life-saving apparel and has for its object the provision of a suit which may be quickly donned over the ordinary clothing and which may be fitted closely to the wearer's body so as to prevent the admission of water between the 10 suit and the body. A further object of the invention is to provide a suit having a novel inflatable portion so that it will be buoyant and will tend to support the wearer in the water for an indefinite period.

20 The invention is illustrated in the accompanying drawings and will be hereinafter first fully described and then particularly pointed out in the claim.

In the drawings:

25 Figure 1 is a perspective view showing the manner of using our improved life-saving apparel;

Fig. 2 is an enlarged view of the suit;

Fig. 3 is a section on the line 3—3 of 30 Fig. 2;

Fig. 4 is a perspective view of the front closure showing the parts separated but approximately in their relative positions.

In carrying out our invention, we employ 35 a flexible fabric material which is impregnated or covered with rubber so that it will be moisture proof and will thereby prevent the entrance of water and will turn the same aside so that the water cannot pass 40 through the material of which the suit is formed. The garment is preferably constructed in the manner of a union suit, with double walls, the inner ply or wall 1 of the material being shaped to provide a body, 45 portion 2, a nether portion 3, and sleeves 4. The sleeves may be formed separately and sewed or otherwise attached to the body portion at the shoulders of the same, but it is preferably to form the entire suit as an integral structure in the usual manner of 50 manufacturing rubber articles. The body portion will have meeting edges or flaps 5 down its open front so that the garment may be easily and quickly donned over the 55 ordinary clothing, and these edges or flaps will be provided with reinforcing and stiff-

ening plates 6 of angular section which will be inclosed in hems 7 formed on the body so that they will be protected against rusting and other deleterious influences. 60 There are provided a plurality of threaded pins or studs 8 swiveled in the outstanding leaf of one plate and engaging openings 9 in the corresponding leaf of the other plate so that the plates and their flaps may be quickly 65 and easily brought together to close the garment and form a water-tight joint. The swiveled end of each stud has a knob or thumb piece 8' pinned or otherwise secured thereto whereby the stud may be rotated. 70 This will be clear from Fig. 4. The reinforcing plates 6 are provided on the distal faces of their outstanding flanges with enlargements 10 so that the screws or pins will have sufficient bearing to hold firmly. The 75 neck portion 11 of the garment will be provided with a gusset 12 and a cord 13 will be laced through the edges of the gusset so that the said neck portion may be drawn close about the neck to prevent the entrance of 80 water into the garment at that point. The wrist portions 14 of the sleeves and the ankle portions 15 will be also provided with the gussets 16 and these gussets will be preferably closed by straps and buckle fasteners 85 17 so that the wrist and ankle portions will be drawn closely about the limbs of the wearer and the garment caused to fit watertight at all points.

Extending over the shoulder portions from 90 the back of the garment and leading down the front portions of the body and around the sides thereof below the sleeves, are outer plies which, with the inner ply at these points, constitute inflatable sacks 18; and 95 the latter are provided with inflating valves 19 at any convenient points of the body on the front of the same so that when the garment is to be used the said sacks may be easily inflated and the desired buoyancy 100 thus attained. These elements 18 when deflated or partly inflated present the appearance in front of two separate sacks simulating the rolling collar and long lapels of a sack coat, spaced from each other in front, 105 and extending well below the waist line and around the hips; but at the back the sacks may unite in a single pouch as seen in Fig. 3. The air pouch thus has the union garment as its inner ply and the sack walls as 110 its outer ply, and the latter is divided in front to correspond with the open front of

the body of said union garment. To facilitate the inflation of the sack, we provide a tube 20 which is constructed at one end to fit over the inflation valve and may be equipped at the opposite end with a mouthpiece as will be understood on reference to Fig. 1. When not in use, the tube may be held by clips 21 on the front of the garment.

From the foregoing description, taken in connection with the accompanying drawings, it will be seen that we have provided a very simple, inexpensive and easily donned garment which may be easily inflated so as to support a wearer in water for a long time. The inflatable portion of the garment will cover approximately the entire body but not the limbs of the wearer so that he will be supported in proper position in the water for swimming and will not quickly become fatigued, hence his strength will be conserved and the chances of being saved by passing vessels consequently increased. The arms and legs of the union suit may be as long as desired; and, if the various fastenings exclude water, none will get under the suit next the wearer. Close fit of the suit gives freedom of movement, and yet the proximate edges of the sacks 18 are spaced to expose the front fastenings. The suit

should be waterproof, but need not be of as heavy material as the outer wall of the pouch because the suit—fitting closely as it does—will not be distended when the pouch is inflated. In other words, the presence of the body in the suit and inside the inner wall of the pouch resists distention thereof inwardly, whereas the outer wall may bulge or stretch outwardly. 35

Having thus described our invention, what is claimed as new is:

Life saving apparel comprising a close fitting waterproof union suit open down the front of its neck and body, fastenings along the edges of said opening, an outer ply of waterproof fabric secured around its edges 40 to said suit and shaped to form two sacks extending from the hips, upward along and spaced from said fastenings; over the shoulders, behind the neck, under the arms, and connected across the back to constitute a flotation pouch whose inner wall is the union suit within the bounds of said edges, and means for inflating said pouch.

In testimony whereof we affix our signatures.

FELIX ZACCARD. [I. S.]
THOMAS P. McDONOUGH. [I. S.]
